UNITED STATES PATENT OFFICE

HANS WIEDEMANN, OF BERLIN-CHARLOTTEBURG, GERMANY

APPARATUS FOR CARBONIZING SOLID CARBONIZABLE MATERIAL

Application filed May 16, 1925, Serial No. 30,703, and in Germany February 18, 1924.

For the distillation of solid bituminous materials, with the purpose of obtaining tar, oil and other products, it is old to use disc plates covered by a gas collecting hood and heated on the bottom.

The invention consists therein, that a disc plate, covered by a hood, contains a fuel inlet and a coke outlet, and a stirring device is so arranged as to move the fuel from the inlet to the outlet round the disc plate. Hereby it is possible on relatively small space and with low heat radiation losses to treat very great masses of fuel, so that high economy is attained and the necessary temperatures can be correctly maintained.

The invention further concerns details, which are later described, and especially a generator for making gas from the coke coming out of the distilling apparatus.

20 An embodiment of the invention is shown in the drawings, in which

Figure 1 is a vertical sectional view of the distilling apparatus.

Figure 1^a is a detail sectional view on the plane indicated by the line 1^a—1^a of Figure 1.

Figure 2 is a similar view of the generator.

Figure 3 is a diagrammatic elevation partly in section of a plant comprising a plurality of the distilling apparatuses and a generator.

Figure 4 is a diagrammatic plan of the same, also partly broken away and in section.

The distilling apparatus according to Fig. 21 consists of a distilling retort with a disc shaped bottom part 1 covered by an air tight top part 2 with a downward bent gas outlet

3. A jacket 4 encloses the retort so as to produce a hollow space for receiving combustion gases and conducting them to a flue 5.

A gas burner 6 heats the disc plate 1. Through the top part and jacket 4 a mechanically driven shaft 7 is connected to the disc plate 1 and provided with stirring arms 8 immediately above the latter. The stirring arms 8 have flanges 9 which extend in the direction in which the arms rotate and cover the spaces between the said arms so as to leave only small free slots between them. Through the walls

45 2 and 4, further, a fuel feeding channel 10 is conducted to the upper side of the arms 8, 9, so as to feed the fuel on the disc plate 1 between the arms 8, 9. A flange 11 is fastened to said channel 10, and extends also in the direction of rotation of the stirring device, and below said flange 11 in the disc plate 1 a coke outlet 12 is arranged, and a conveyor 13, driven by a pulley 14 is inserted into said outlet 12.

55 The operation is as follows: The material to be distilled, which may be vegetable, waste, peat, brown coal, anthracite, oleiferous shale or the like, slides down through the feeding channel 10 between the stirring arms 8, and by the latter it is slowly conducted round the disc plate 1, which is heated to 400–600° centigrade. Thereby the volatile matter is distilled off and removed through the outlet 3; the residual coke drops to the outlet 12 for being removed by the conveyor 13. In this way a very uniform low temperature distillation of the fuel is attained, and tar, paraffine, lighting gas and eventually petrol or gasoline are gained; these products are produced in a dust free state as in all parts of the apparatus only very slow movements are produced and the material is nowhere dropped freely downward.

65 The gas generator according to Fig. 2 consists of a pear-shaped casing 15 and a similarly shaped core 16, which latter is fastened to a mechanically driven shaft 17. The casing 15 is fitted on its top part with a fuel feeding opening 18, through which the coke falls down to the space between the casing 15 and the core. A gas outlet 19 is similarly provided.

70 In the casing walls, channels 20 for feeding air and further channels 21 for feeding water or vapor are contained, for instance in the shape of annular or spiral channels. The said channels have outlet openings or nozzles directed against the inner space of the generator. Similar channels may also be contained in the core 16 with the special purpose of cooling it. This rotatable core 16 is fitted on its outer face with spur like projections 24 which serve to stir the material and cause its downward movement.

75 The operation is the following. The coke, 100

entering in the top part, fills up the hollow space nearly to its top and is burnt to carbon monoxide by the air fed through the channels 20 in regulable quantities. The superfluous heat arising thereby is utilized for producing water gas or mixed gas by feeding regulable quantities of steam through the channels 21. Thereby the coke in slowly sinking down is reduced to ashes, which are drawn off at 25, whilst the water gas flows off at 19.

Fig. 3 shows several fuel distilling apparatuses of the type shown in Fig. 1 connected in series for fractional distillation, and a gas generator of the type shown in Fig. 2 is immediately attached for further gasifying the coke obtained from the first plant. The screw conveyors 13 are of such length, and the distilling chambers are arranged so obliquely one above the other, that every conveyor extends from the fuel outlet 12 of the one chamber to the fuel feeding channel 10 of the next chamber, so that the fuel automatically runs through the whole row of distilling chambers and then immediately to the feeding opening 18 of the gas generator 15. In this way the whole distilling and gasifying process is effected quickly and automatically so as to avoid all heat losses.

For heating, each distilling chamber is provided with a gas burner 6, and the waste heating gases are conducted from the flue 5 of this chamber to the heating jackets of the further chambers each after another; thereby the gas heat is utilized in an inverse current system. According to the outer conditions it is also possible to heat the distilling chambers partly or entirely by the sensible heat of the generator gas by conducting the gas from the generator outlet 19 to the heating jackets 4 of the distilling chambers and thereby utilize their heat content available at a temperature of about 800° centigrade.

The generator gas can be used for the operation of the burner 6, and further for gas motors or for heating steam boilers, so that with advantage a power plant, as for instance an electric current generating plant may be immediately added. For heating steam boilers the generator gases are advantageously burnt in their hot condition, with which they come from the generator; thus this heat is utilized for producing very hot heating flames.

I claim:

1. Apparatus for carbonizing solid carbonizable material, comprising a substantially horizontal disc plate, means for heating the same from below the same, a hood tightly covering said plate and provided with a charging means for feeding solid material on to said plate at one side thereof, a discharging means, adjacent said charging means, for discharging solid material from said plate, and a rotary stirring device adapt-

ed to move solid material around on said plate from adjacent said charging means to said discharging means, the said charging means comprising a duct extending through the hood and having its discharge end arranged close to and directly above the stirring device. 70

2. Apparatus as claimed in claim 1 in which said stirring device consists of a rotatable shaft and substantially radial arms, 75 said arms having flanges on the upper edges thereof extending in the direction of rotation of said arms so as to nearly cover the spaces between the arms.

3. Apparatus as claimed in claim 1 in 80 which charging means is provided with a baffle flange extending above and screening the discharging means.

In witness whereof I affix my signature. 85
